UNITED STATES PATENT OFFICE.

GEORGE H. CLARK, OF MELROSE, MASSACHUSETTS, ASSIGNOR TO CROSBY STEAM GAGE & VALVE COMPANY, OF BOSTON, MASSACHUSETTS, A CORPORATION OF MASSACHUSETTS.

PRESSURE GAUGE.

Application filed December 5, 1919. Serial No. 342,816.

This invention relates to that well known type of pressure gauge in which a Bourdon spring tube is employed and in which the pressure is indicated by mechanism comprising a sector actuated by the spring tube and in turn rotating a pinion on whose shaft is mounted an index hand which indicates the pressures on a dial; with which combination it is customary to control the pinion shaft by a hair spring so arranged as to take up the backlash between the sector and the pinion; but it appears that such employment of the hair spring is unsatisfactory as it produces a rotative force in the pinion shaft, not by means of a rotative couple, but by a single force acting in a certain direction and with a given leverage, thereby producing irregularities or errors, of which the most pronounced are indicated at points diametrically opposite on the gauge dial; and one serious result of all this is the necessity of making the dials, particularly those of the larger gauges, individually, as a standard marked dial would not accurately indicate the pressures.

The object of the present invention is to do away with the hair spring and to substitute therefor a spring acting directly through the sector and producing a thrust which acts always in the same direction and on the line of centres of the sector and pinion, thereby following a fixed law and making possible the employment of standard marked dials in all cases.

To accomplish this object I employ a triple sector comprising two outer sectors relatively fixed and preferably made of one piece, to which the spring tube is indirectly attached, and a middle sector rotatively mounted between them on their common axis, which three sectors engage the pinion; and, to take up the backlash between the triple sector and the pinion, I provide the middle sector with a controlling spring which constantly exerts pressure thereon, thereby insuring a complete engagement of the sectors with the pinion by causing the teeth of the sectors as a combination to accommodate themselves to the spaces between the teeth of the pinion, however much these spaces may vary.

The invention is illustrated by the accompanying drawings in which:—

Fig. 1 is a view of the dial reduced in size;

Fig. 2 is a view of the gauge with the case 55 and dial removed;

Fig. 3 is a plan view looking in the direction of the arrow Fig. 2.

The gauge case 1, frame 2 encased therein, dial 3, index hand 4, pinion shaft 5, pinion 6, and linkage 7 connecting the spring tube 8 with the sector 9 are all combined in a well-known manner and need not be described. The triple sector 9 comprises three sectors, namely, the two outside sectors 9^a, 9^b and the 65 middle sector 9^c, all having a common axis 10 journaled in frame 2 and all engaging the pinion 6; the sectors 9^a, 9^b constituting a forked sector made of one piece and connected through linkage 7 with spring tube 70 8; and the middle sector 9^c being engaged and controlled by the spring 11 affixed to the inner end 12 of the forked sector 9^a, 9^b.

I claim:

1. In a pressure gauge, in combination, a 75 Bourdon spring tube; a sector; mechanism operatively connecting the spring tube with the sector; a pinion engaged and actuated by the sector; and indicating means actuated by the pinion; the sector comprising a forked 80 member, operatively connected with the spring tube, and a rotatively spring controlled intermediate member; and the members having a common axis and engaging the pinion; together with the controlling spring. 85

2. A pressure gauge having, in combination, an operating tube, a toothed sector, operating connections between the tube and sector, indicating means, a pinion connected therewith and meshing with the sector, and 90 a second sector having the same pitch and axis of rotation as the first sector and also meshing with the pinion, and yielding connections between the two sectors for normally imparting a relative rotation to cause a 95 close engagement of the teeth of the pinion and avoid backlash between the pinion and first-mentioned sector.

In testimony whereof I have affixed my signature.

GEORGE H. CLARK.
